UNITED STATES PATENT OFFICE

163,386

COMBINATION CAN AND BOTTLE OPENER

Baraket L. Herro, Milwaukee, Wis.

Application January 24, 1950, Serial No. 7,454

Term of patent 14 years

(Cl. D22—2)

To all whom it may concern:

Be it known that I, Baraket L. Herro, a citizen of the United States, residing at Milwaukee, in the county of Milwaukee and State of Wisconsin, have invented a new, original, and ornamental Design for a Combination Can and Bottle Opener, of which the following is a specification, reference being made to the accompanying drawing, forming a part thereof.

I claim:

The ornamental design for a combination can and bottle opener, as shown.

BARAKET L. HERRO.
